COMBUSTION FLASK FOR LIQUID OXIDANTS
AND FUELS

Robert H. Canfield, Newport, R.I., assignor to the United States of America as represented by the Secretary of the Navy

Filed Dec. 16, 1944, Ser. No. 568,528

11 Claims. (Cl. 60—39.46)

(Granted under Title 35, U.S. Code (1952), sec. 266)

This invention relates to combustion apparatus, and particularly to the rapid generation of expanding gases, adapted to drive engines or actuate other machinery. The principal object of the invention is to provide improved, extremely compact and efficient means for the generation of such gases, said means being particularly useful in powering the propelling apparatus of underwater torpedoes, although equally applicable to the driving of vessels or other vehicles.

The present invention constitutes a further development of that disclosed in my copending application Serial No. 100,686, now Patent 2,746,249 filed jointly with Francis R. Bichowsky under date of September 14, 1936, entitled "Combustion Apparatus and Method."

Another important object of this invention is to provide an improved combustion flask particularly adapted for use in conjunction with the combustion cycle disclosed in the aforementioned copending application.

A further object is to provide such an improved combustion flask having its parts so arranged that the comburents are preheated prior to their final admission to the combustion space, and so designed that all parts are effectively protected against the development of temperatures which might damage the apparatus.

Other objects and advantages will be apparent upon consideration of the present disclosure in its entirety.

In the drawings:

Fig. 1 is a substantially diametric longitudinal sectional view of a combustion flask incorporating the principles of the present invention;

Fig. 2 is an end view thereof; and

Fig. 3 is a cross sectional view taken substantially on the line 3—3 of Fig. 1 and looking in the direction of the arrows.

Referring now to the drawings, reference character 1 designates the flask body, which may be cast of heat-resistant metal or other suitable material in substantially cylindrical form, and which is provided at its outlet end with a domed cover 2. Projecting inwardly from the substantially cylindrical interior surface of the flask body is a continuous helical rib 3 of relatively high pitch which assists in positioning and fits tightly against the outer liner sleeve 5. Sleeve 5 forms a spaced inner wall and is longitudinally held between the cover 2 and the opposite closed end of the body, as clearly shown in Fig. 1. This arrangement will be seen to provide a helical passageway 4 between the outer wall of flask 1 and the sleeve 5 the interior of which constitutes the combustion chamber C. Communicating with one end of such passageway is an inlet nipple 7 constituting a mixing chamber in which a confluence of a decomposable comburent occurs, threaded into a boss 8, while the other end of the passageway communicates with the interior of sleeve 5 through slots 9, a plurality of which are peripherally provided in the end of the sleeve, as also shown in Fig. 1.

Axially positioned within the sleeve 5 is an inner liner or burner tube 10, secured to the inlet end of the flask body 1 by screws 12 extending through the end boss 14.

2

The flask 1, sleeve 5 and tube 10 comprise an assembly of outer, intermediate and inner cylinders. Boss 14 also supports the fuel nozzle 15, projecting therethrough in axial position and discharging longitudinally into the assembly in such manner as to project the fuel through the burner tube into the core of the combustion chamber. The burner tube is also exteriorly provided with a helical rib 17 of a relatively lower pitch than that of the rib 3, which assists in supporting and centering it within the sleeve 5 and provides a passageway 6 constituting a continuation of the passageway 4, with which it communicates through the slots 9 as previously indicated. The helical ribs of two pitches whirl the mixture at progressively higher rates. The mouth of the burner tube 10 is bevelled as indicated at 11, the rim of the bell being of somewhat lesser diameter than the internal diameter of the sleeve 5, to provide an annular passage 13 there-around of restricted cross section.

Formed longitudinally in and for a substantial part of the length of the burner tube near the discharge end thereof are a plurality of slots 20, cut entirely through its wall, each slot being inclined or non-radial with respect to the axis in such manner as to lie on or tangent to a spiral described about such axis, as indicated in Fig. 3, and extending inwardly in the direction of flow through the helical passage 6. Each slot is provided with an outer edge 20a disposed relative to the direction of flow, indicated by the arrow in Fig. 3, to serve as a scoop and direct lighter gasified components of the substances flowing through passage 6 into the burner tube through a slot. The restriction at 13 tends to maintain a back pressure in passageway 6 such that the expansion therein will assure movement of the gas into the slots 20, while heavier decomponents, which may include any remaining liquid, are sprayed through passage 13 and into the form of an envelope of the liquid along the inner wall of sleeve 5, entering the combustion space C where they are ignited by the burning fuel.

Nipple 7 is provided with two inlet portions, one comprising the spray holder 22 threaded into its end and provided with a whirl-type jet assembly 24 to which connection is adapted to be made at the coupling 23 and the other comprising lateral inlet coupling 25, which provides for admission of fluid material in a manner to insure its intimate admixture with the material entering through jet 24. As disclosed in the aforementioned copending application, one of these materials may be an initially liquid substance such as H_2O_2 , adapted to decompose to provide oxygen to support combustion. This material may be introduced at 25, oxygen evolving therefrom as it advances through the helical passages 4, 6. Another liquid, comprising a catalyst such as sodium permanganate in a liquid solution adapted to promote the decomposition of the hydrogen peroxide, may be introduced through the coupling 23. Such decomposition is also assisted by the heat absorbed from the combustion chamber.

The fuel is preferably also introduced through a whirl-type nozzle 30. Provision is made for igniting the fuel in the conventional manner, an igniter holder 33 being provided adjacent the fuel nozzle and communicating interiorly with an annular chamber 34 surrounding such nozzle and also discharging into the interior of the burner tube 10, as shown. The holder 33 is adapted to support an igniter 50 which may be of the usual or any desired form.

In advancing through the passages 4, 6, the hydrogen peroxide is preheated and largely decomposed, and some or all of the water resulting from such decomposition is vaporized. This results in absorption of large quantities of heat from the walls of the burner tube 10 and other components within the flask imparting a strong cooling

action and tending to prevent overheating of any part of the assembly.

The products of combustion are delivered to the engine or other propelling means (unshown) through a dry pipe, or other means (also unshown) attached to the discharge coupling boss 35.

The invention herein described may be manufactured and used by or for the Government of the United States of America for governmental purposes without the payment of any royalties thereon or therefor.

I claim:

1. A combustion device of the character described comprising a casing, burner means comprising a tube within the casing, said tube at its one end abutting the interior of said casing, and the other end thereof projecting and opening into the interior of the casing, fuel feeding means discharging longitudinally into that end of said tube which abuts the casing, means for feeding comburent material to the casing, means forming a helical passage circumscribing said tube for feeding such comburent material longitudinally within the casing while imparting to said material a rotation substantially about the axis of said tube, and means defining inwardly directed passages to which said material is delivered while in rotation, the inner ends of said passages opening near the free end of said tube whereby said comburent material may be mixed with the fuel and burning may occur in the vicinity of the mouth of said tube.

2. A combustion device of the character described comprising a substantially cylindrical elongated casing, at least a part of said casing being double walled, burner means comprising a tube within said casing, said tube at its one end abutting the interior of said casing, the other end of said tube projecting and opening into the interior of the casing and being spaced from the inner one of said double walls, fuel feeding means discharging longitudinally into that end of said tube which abuts the casing, means for feeding comburent material to the space between the said double walls of the casing, a helically arranged guide wall within said space forming a passageway extending around and longitudinally of but spaced from said tube, for imparting rotation to such material while conducting it longitudinally of the casing, additional helically arranged guide wall means between said tube and inner wall forming a continuation of the first mentioned passageway and connected thereto by openings in said inner wall, the continuation passageway discharging into the interior of the casing adjacent the open end of said tube.

3. A combustion device as set forth in claim 2 including scoop means carried by the tube near its open end, said scoop means being connected at their outer ends to said continuation passageway and at their inner ends to the space within said tube, whereby lighter components of the comburent material traveling through said continuation passageway may be directed into said tube while heavier components are discharged from the passageway adjacent the mouth of the tube.

4. A combustion device of the character described comprising an outer flask, burner means including a wall spacedly mounted within said flask, means for introducing a comburent material into the space between said flask and wall, means defining a generally helical passageway imparting rotation to such material while conducting it lengthwise through said space, means defining a continuation passageway also of helical form and serially connected to the first mentioned passageway and extending counter to and arranged within the same, and burner means including jet-type fuel feeding means discharging into the space bounded by said last mentioned passageway and directed longitudinally of the assembly in the direction of advance of said last mentioned passageway, said passageway discharging into a zone of combustion of fuel projected by said feeding means and said comburent material being adapted to be preheated in said passageways.

5. In combination with means as set forth in claim 4, centrifugal separating means appurtenant the discharge end of the second mentioned passageway for directing a part of said comburent material into said zone and for simultaneously directing heavier components of said material longitudinally in the form of a film surrounding said zone.

10 6. A motive fluid generator comprising a flask, means for injecting and igniting a fuel at one end of the flask to impel a volume of hot gas to the other end and terminal of the flask, means for producing a confluence into the flask of a mixture of an oxygen-carrying liquid and a catalyst for the immediate promotion of decomposition of said liquid, means initially separating said mixture from said volume of gas but diverting a light constituent of the decomposition to support the combustion of the fuel, and constricted means through which a heavy constituent of the decomposition is injected into the terminal volume of gas to complete the motive fluid and at the same time maintain a back pressure to force the foregoing diversion of said light constituent.

15 7. A combustion device of the character described comprising an outer flask, means defining a combustion chamber within said flask, burner means including fuel feeding means opening into the combustion chamber, means for feeding comburent material into said flask, means for imparting rotation to such material while it is passing through said outer flask before it enters said chamber, and means providing communication between 20 said flask and chamber whereby the rotating comburent material may enter the combustion chamber after passing through said flask, said last named means including centrifugal separating means arranged to direct lighter components of said comburent material inwardly into said combustion chamber and to direct heavier components thereof longitudinally in the form of a film at least partially surrounding said chamber.

25 8. A combustion device of the character described comprising a casing, burner means comprising a tube within the casing and abutting the same at one end but projecting into the casing and having its side walls spaced therefrom and its other free end opening into the casing, fuel feeding means discharging longitudinally into said tube at the end thereof which abuts the casing, means for feeding additional comburent material to the casing and through and into said tube near its free end whereby such material may combine with the fuel and burning may take place within said casing in the vicinity of the mouth of said tube, and centrifugal separating means connected to said means for feeding additional comburent material, said centrifugal separating means discharging lighter components inwardly in a direction to mix with the burning fuel, and discharging heavier components longitudinally in the form of a layer surrounding at least a part of the burning zone.

30 9. A motive fluid generator comprising a mixing chamber adapted to receive a confluence of oxygen carrying liquid and a catalyst for promoting decomposition of said liquid, an assembly comprising outer, inner and intermediate substantially concentric cylinders disposed in spaced relation to provide a first annular space between the outer and intermediate cylinders and a second annular space between the intermediate and inner cylinders, the space within the inner cylinder forming a burner chamber and communicating at one end thereof with a combustion chamber, wall means within the first annular space forming a first helical passageway therein, wall means within the second annular space forming a second helical passageway therein, means communicating adjacent ends of the first and second passageways, means communicating the mixing chamber and first passageway, means communicating one end of the second passageway with the combustion chamber, means communicating an intermediate portion of the second passageway with the burner chamber, and a fuel injector

adapted to discharge fuel into the burner chamber.

10. A motive fluid generator comprising; a mixing chamber adapted to receive a confluence of an oxygen carrying liquid and a catalyst for promoting decomposition of said liquid, means for receiving the confluent mixture and whirling same at progressively higher rates to thereby separate the decomponents, a burner chamber, a combustion chamber communicating with the burner chamber and with the means for whirling the mixture, means for injecting fuel into the burner chamber, and means for delivering separated decomponents respectively into the burner chamber and into an envelope form within the combustion chamber.

11. In a motive fluid generator, an inner cylinder having apertures through the wall thereof, the space within the inner cylinder forming a burner chamber, a concentric outer cylinder disposed in spaced relation around the inner cylinder, means providing a helical passageway be-

10

15

tween the cylinders, means for delivering oxygen carrying liquid to said passageway, a combustion chamber communicating with one end of the burner chamber, an annular space communicating one end of the helical passageway with the combustion chamber constructed to restrict flow of heavier constituents of liquid escaping therethrough and effecting a back pressure within the helical passageway to thereby force lighter constituents inwardly through said apertures.
